UNITED STATES PATENT OFFICE.

JOSEPH L. SOMERS, DANIEL M. SOMERS, AND WILLIAM H. ATKINSON, OF BROOKLYN, NEW YORK.

DESIGN FOR A BOX.

SPECIFICATION forming part of Design No. 15,119, dated July 1, 1884.

Application filed March 14, 1884. Term of patent 14 years.

To all whom it may concern:

Be it known that we, JOSEPH L. SOMERS, DANIEL M. SOMERS, and WILLIAM H. ATKINSON, all of the city of Brooklyn, county of Kings, and State of New York, have jointly invented and produced a new and original Design for Boxes, of which the following is a specification, reference being had to the accompanying fac-similes, forming part hereof.

10 In said fac-similes of this design several boxes are shown that embody it, Figures 1, 2, 3, 4 being elevations of as many boxes differing slightly from each other in form, but all embracing said design; and Fig. 5 represents the design embraced in the can shown in Fig. 3 by a vertical sectional elevation.

That the new shape or configuration may be more fully understood, it will be described by reference to the fac-similes.

20 The body of the box is rectangular, and the corners uniting the four sides (two, A B, alone being seen) are rounded, as at 2. The upper extremities of said sides and rounded corners have an edge enlargement or bead, 3. The 25 top proper of the box is depressed, so as to form a channel, 4, next to the top edges of said sides, and rises from said channel in a curved or arched form, that produces a dome-like top, C, the central portion of which rises to 30 form a vertical wall, 5, having a horizontal cover-plate, D. The dome-like top C will vary with any change of dimensions in the 35 rectangular shape of the body. Thus its base will elongate as the shape of the rectangular body has two of its sides increased, (see Fig. 1 as compared with the other figures,) and hence the curve of this dome-like top may be greater or less than is shown, or include more than one arc, as in Fig. 4, where the curved 40 shade-line may indicate the junction of two arcs united to form the dome-like top without departing from the design. The vertical wall 5 of the top may be circular, rectangular, as in Fig. 2, or have any other form, considered horizontally, and still be within the 45 scope of this design, and the cover-plate D, shown in connection with it, may be omitted without modifying the shape or configuration; but when present does not change the 50 same. The said vertical wall 5 may have the projecting bead 6 at the point of meeting with the dome-like top; or the same may be omit-

ted, as is shown in Figs. 1, 3, 4, and 2, the former showing said bead and the latter a box without it. When the vertical wall is 55 made rectangular, as in Fig. 2, its corners should conform, by means of curves, with the similar shape of the box-body. The projecting bead 6 may be single, as shown in Figs. 3 and 4, or be made double, as is seen in Fig. 1.

The bead or projection 7 at the bottom edge of the box-body, where the sides join the bottom, may be used or omitted without varying the design, the essential characteristics of 65 which are, first, a rectangular body with curved corners; second, a bead or enlargement at the upper edges of the sides; third, a dome-like top depressed or channeled at its union with the sides; fourth, a vertical wall 70 rising from the center of the dome-like top. A box having this shape or configuration may be further beautified by the addition of other ornamental effects, due to surface-ornamentation of any kind.

75

What is claimed is—

1. The design for the shape or configuration of a box, the same consisting in a rectangular body with curved corners, a bead or enlargement at the upper edges of its sides, 80 a dome-like top depressed at its line of union with said sides, from which dome-like top a vertical wall rises centrally, substantially as described.

2. The design for a box, the same consisting of the shape or configuration formed by the rectangular body, its curved corners, a bead or enlargement at the upper edges of the sides, the dome-like top depressed at the point of its union with said sides, the vertical wall 90 rising centrally from said dome-like top, and the bead or enlargement at the point of meeting of said vertical wall with the dome-like top, substantially as described.

In testimony whereof, we have hereunto set 95 our hands in the presence of two subscribing witnesses.

JOSEPH L. SOMERS.
DANIEL M. SOMERS.
WM. H. ATKINSON.
